UNITED STATES PATENT OFFICE.

JOHN BURKHARDT, OF NEW YORK, N. Y.

DESIGN FOR A FIRE-GRADE.

SPECIFICATION forming part of Design No. 17,019, dated December 7, 1886.

Application filed November 3, 1886. Serial No. 217,009. Term of patent 7 years.

To all whom it may concern:

Be it known that I, JOHN BURKHARDT, residing at New York, in the county and State of New York, and a citizen of the United States, have invented and produced a new and original Design for Fire-Grates or Coal-Baskets, of which the following is a specification, reference being had to the accompanying drawings, forming part thereof.

Figure 1 is a perspective side elevation of my newly-designed fire-grate or basket, and Fig. 2 is a top view of the same.

Heretofore fire-grates have been made which presented, when viewed in elevation, as in Fig. 1, a vertically-slotted appearance, the slots terminating in horizontal bands at their bottom and top, without any other features or ornamentation.

The leading features of my design consist in a series of longitudinal rows of connected angular projecting loops *a*, shown in demi-relief, embracing upright curved rectangular arms *b*. These features present the appearance of bask-

et-work, showing rows of square intermediate openings, the loops being connected by straight 25 flat bars or ribs *c* in the central plane of the design.

Fig. 2 exhibits the features above described and the pointed end or apex of the arms *b*, also the beveled base-plate *c*, with legs *d*, 30 shown in Fig. 1.

From the base upward the design has a curved outline, and the undulations of its surface, composed of the features described, constitute in ensemble a highly ornamental design. 35

I claim—

The design for a fire-grate or coal-basket herein shown and described, the same consisting of the representation of rows of connected projecting angular loops *a* and of arms *b*, forming an undulating surface or outline. 40

JOHN BURKHARDT.
